United States Patent

Des. 241,353

Patented Sept. 7, 1976

241,353

CIGARETTE LIGHTER

Pierre Marie Francois Martin, 74 Rue St. Lazare,
Paris, France

Filed July 10, 1974, Ser. No. 487,180

Claims priority, application France Jan. 10, 1974

Term of patent 14 years

Int. Cl. D27—05

U.S. Cl. D27—42

FIG 1

FIG 2

FIG 3

FIG 4

FIG 5

FIG. 1 is a top plan view showing a cigarette lighter of my new design;

FIG. 2 is a front elevational view of the cigarette lighter shown in FIG. 1;

FIG. 3 is a side elevational view of the cigarette lighter shown in FIG. 1 with the other side being substantially identical to the side shown;

FIG. 4 is a rear elevational view of the cigarette lighter shown in FIG. 1; and

FIG. 5 is a bottom plan view of the cigarette lighter shown in FIG. 1.

I claim:

The ornamental design for a cigarette lighter, as shown.
